UNITED STATES PATENT OFFICE.

HERMAN HOFGREN, OF CHICAGO, ILLINOIS.

ASH-SIFTER.

No. 797,115.

Specification of Letters Patent.

Patented Aug. 15, 1905.

Application filed October 17, 1904. Serial No. 228,727.

To all whom it may concern:

Be it known that I, HERMAN HOFGREN, a citizen of the United States, residing at Chicago, in the county of Cook and State of Illinois, have invented certain new and useful Improvements in Ash-Sifters, of which the following is a specification.

This invention relates to improvements in a device for sifting ashes, so as to separate the pieces of coal and unconsumed particles from the ashes or finer pieces; and it consists in certain peculiarities of the construction, novel arrangement, and operation of the various parts thereof, as will be hereinafter more fully set forth and specifically claimed.

The principal object of the invention is to provide an ash-sifter which shall be simple and inexpensive in construction, strong, durable, and effective in operation, and so made that its parts will be inclosed, so as to prevent the escape of dust in the sifting operation.

Another object of the invention is to so construct the device that the ashes or finer particles will be deposited in a suitable receptacle for the same, while the pieces of coal and coarser particles will be deposited in a receptacle for them.

A still further object of the invention is to provide a perforated trough wherein the ashes may be deposited and stirred on its way to the sifting-cylinder.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a longitudinal sectional view of an ash-sifter embodying my invention, showing it mounted on a portion of a barrel to receive the sifted ashes. Fig. 2 is a rear end view showing a portion of the casing broken away to disclose the interior mechanism. Fig. 3 is a transverse sectional view taken on line 3 3 of Fig. 1 looking in the direction indicated by the arrows; and Fig. 4 is a similar view taken on line 4 4 of Fig. 1 looking in the direction indicated by the arrows, but showing the stirring-arms and crank-shaft removed.

Like numerals of reference refer to corresponding parts throughout the different views of the drawings.

The reference - numeral 10 represents the casing, which may be of any suitable size, form,

and material, but preferably rectangular in shape, as shown, and of wood. The bottom of the casing is formed with an opening 11, through which the sifted ashes may pass into a barrel 12 or other suitable receptacle. Extending across the casing is a partition 13, which depends from the upper surface to about midway between the top and the bottom of the casing and has in its lower portion a recess 14 to permit of the rotation of the stirring-arms for the trough or fixed sieve of the sifter. The other portion of the casing 10, between its front end and the partition 13, is closed by means of a removable cover 15, having a handle 16, by means of which it may be removed when it is desired to deposit ashes in the casing. Extending across the lower portion of the casing is a partition 17, which is inclined from the front edge of the opening 11 toward the front end of the casing and has in its upper portion a curved recess 18 to receive and support the front end of the stationary trough 19, which is shown as being made of perforated material, but which may be made of wire-cloth or other foraminous material. This trough is substantially semicircular in shape, but is contracted toward its free end and is located in an inclined position, as is clearly shown in Figs. 1, 3, and 4 of the drawings. Horizontally and longitudinally journaled in the front end of the casing is a shaft 20, which has on its outer end a crank-handle 21, used for rotating the sifting-cylinder 22, which is shown as being made of perforated sheet metal, but which may be made of any suitable foraminous material. This cylinder is slightly enlarged toward its rear end and is provided at said end with a strengthening rim or band 23, to which are secured at one of their ends a number of arms 24, the other ends of which are secured to a stub-shaft 25, journaled in the rear end of the casing. As shown in Fig. 1 of the drawings, the cylinder 22 is located longitudinally within the casing so that its front end, which is open, will receive the rear end of the trough 19, which, as before stated, is downwardly and rearwardly inclined. The front portion of the cylinder 22 is provided with a band or ring 26, to which are secured at one of their ends a number of stirring-arms 27, the other ends of which are secured to the inner end of the crank-shaft 20, which end of said shaft projects into the upper portion of the trough 19, as is clearly shown in Fig. 1 of the drawings. By reference to Figs. 1, 2, and 3 of the drawings it

will be seen that the arms 27 are slightly twisted or laterally deflected, so that when the crank-shaft 20 is turned and the cylinder 22 rotated thereby the arms 27 will stir the ashes in the trough 19 and will act upon the same somewhat in the manner of a spiral conveyer, thus forcing the ashes from the trough into the cylinder, by means of which the ashes will be separated from the coal and coarser particles, which will pass from the rear end of the cylinder 22 out through an opening 28 in the rear lower portion of the casing to a coal-bucket 29 or other suitable receptacle.

From the foregoing and by reference to the drawings it will be seen and readily understood that by removing the cover 15 from the upper front portion of the casing ashes may be placed within the trough 19, when the cover may be replaced and the operation of sifting performed by turning the crank-handle 21, which, as before stated, will rotate the cylinder 22 and stir the ashes within the trough, by means of which a part of the sifting operation will be done. As the crank-shaft continues in its rotation it is apparent the arms 27 will stir the ashes, break up the lumps therein, and will force the contents of the trough rearwardly into the cylinder, from which the finer particles will pass through the opening 11 and when desired into a suitable receptacle 12 placed thereunder.

The openings 11 and 28 in the bottom of the casing are divided by means of oppositely-inclined pieces 30 and 31, which extend across the bottom and, together with the inclined pieces 32, located at the side edges of the casing, form discharging-hoppers for the ashes and coal and coarser particles.

Having thus fully described my invention, what I claim as new, and desire to secure by Letters Patent, is—

1. In an ash-sifter, the combination with the casing, of a stub-shaft journaled in the rear end of the casing, a foraminous cylinder rotatably mounted therein and having open ends, a number of supporting-arms secured at one of their ends to the stub-shaft and connected at their other ends to the rear end of the cylinder, a foraminous trough mounted in an inclined position in the casing and adapted to discharge at its lower end into one end of the cylinder, a crank-shaft journaled on the casing and projecting into and terminating near the end of the raised portion of the trough, a series of arms secured at one of their ends to the inner portion of the crank-shaft and at their other ends to the cylinder, substantially as described.

2. In an ash-sifter, the combination with the casing, of a stub-shaft journaled in the rear end thereof, a frustum-shaped and foraminous cylinder rotatably and longitudinally mounted therein and having its ends open, a number of supporting-arms secured at one of their ends to the stub-shaft and connected at their other ends to the rear end of the cylinder, a circular-shaped and foraminous trough mounted in an inclined position in the front part of the casing and having its lower end projecting into the front end of the cylinder, a crank-shaft journaled on the casing and projecting into and terminating near the end of the raised portion of the trough, a series of arms secured at one of their ends to the inner portion to the crank-shaft and connected at their other ends to the periphery of the cylinder near its front end, said arms being laterally deflected from the securing-points of their front ends, substantially as described.

HERMAN HOFGRENN.
